[57] CLAIM

The ornamental design for a combination funnel and plastic bag stand for home-made frozen flavored drink popsicles, as shown and described.

DESCRIPTION

FIG. 1 is an exploded front elevational view of the combination funnel and plastic bag stand for home-made frozen flavored drink popsicles showing my new design;
FIG. 2 is an exploded rear elevational view thereof;
FIG. 3 is an exploded right side view thereof;
FIG. 4 is an exploded left side view thereof;
FIG. 5 is a top plan view thereof;
FIG. 6 is a bottom plan view thereof; and,
FIG. 7 is a right side view thereof with the funnel inserted into the stand portion.
